DESIGN FOR AN ELECTRIC HEATER

James J. Gough, Chicago, Ill.

Application July 20, 1939, Serial No. 86,121

Term of patent 7 years

To all whom it may concern:

Be it known that I, James J. Gough, a citizen of the United States, residing at Chicago, Cook County, Illinois, whose post-office address is 6333 West Sixty-fifth Street, Chicago, Illinois, have invented a new, original, and ornamental Design for an Electric Heater, of which the following is a specification, reference being had to the accompanying drawing, forming a part thereof.

Figure 1 is a front perspective view of an electric heater embodying my design; and

Figure 2 is a side view of the design shown in Figure 1.

The dominant features of my design reside in the portions illustrated in solid lines.

I claim:

The ornamental design for an electric heater, substantially as shown and described.

JAMES J. GOUGH.
